UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,808, dated March 14, 1882.

Application filed February 11, 1882. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a flower with surrounding petals or leaves. B is a group resembling the acanthus leaf, with an upwardly-curving S-shaped branch, S, (shown in part at each end of the photograph,) consisting of a series of irregular recurring leaf-forms growing out from and along a common stem. On a stem projecting downward from B and toward the left is the group C, a central bell-shaped flower, surrounded by scroll-like leaves with a larger scroll-like leaf, projecting downward and to the right. Above C is a disconnected star-shaped flower, a, with a depending bell-like flower, b. D is another flower and scroll-leaf figure projecting from C; E, a similar flower projecting from D, and G an oval-shaped flower projecting upward from E. From D the main stem projects with an upward curve and forks, the upper fork bearing the fan-like scalloped flower F, and the branching leaf-scroll H, having one head drooping over toward the right and the other and smaller toward the left, over the disconnected star-shaped flower and scroll-leaf cluster K, and the other fork, which recures downward, bearing a bell-shaped leaf-figure, L, with a central star-shaped flower and a leaf-spray springing upward. Two stems spring downward from L. The one on the left bears a bell-like flower, e, from which projects a branching scroll-leaf cluster, M, (shown

in part on each side of the photograph,) bearing a flower, d, similar to F, and finally the group B, above described. The other stem 45 from L bears the star flower figure N, with a projecting star-flower below and a larger one above, also the acanthus-like spreading-leaf scroll O, curving toward the left below, (shown in part on each side of the photograph.) P is 50 an upward-curving bell-shaped flower-figure. Q, forking from the same stem, is a similar scroll-leaf figure, with projecting flowers e f terminating in the flower and scroll group R, curving to the left, from which springs the 55 group T, curving upward, with connected flowers. The open flower h springs from the flowering branch U, which curves over h to the left and forks, forming the upper flower and leaf group, V, and the lower flowering stem, i, 60 terminating in a larger bell-shaped flower. Below i is a small group, j, consisting of a circular flower and a fan-like flower. From the bell-shaped petaled flower-figure W springs above and to the right the flower and leaf 65 group k, consisting of two large circular flowers and one fan-shaped flower and connected leaves, sprays, and blossoms, above and to the left the figure P, and to the left and downwardly the open flower-group l, set on a rec 70 curving branching stem. m is a circular flower-group, set on a recurring stem and terminating below in a branching stem and flower figure, n, having bell-shaped and open flowers.

I claim—

The design for carpets, consisting of the groups and figures A B C D E F G H K L M N O P Q R S T U V W a b c d e f g h i j k l m n, with connected parts, substantially as shown.

WINTHROP L. JACOBS.
